(57) **CLAIM**

The ornamental design for a LED bulb, as shown and
described.

DESCRIPTION

FIG. 1 is a perspective view of a LED bulb;
FIG. 2 is a front view of the LED bulb depicted in FIG. 1;
FIG. 3 is a left side view of the LED bulb depicted in FIG.
1;
FIG. 4 is a top view of the LED bulb depicted in FIG. 1; and
FIG. 5 is a bottom view of the LED bulb depicted in FIG.
1;
FIG. 6 is a photograph showing a perspective view of the
LED bulb depicted in FIG. 1;
FIG. 7 is a photograph showing a front view of the LED bulb
depicted in FIG. 1;
FIG. 8 is a photograph showing a rear view of the LED bulb
depicted in FIG. 1;
FIG. 9 is a photograph showing a left side view of the LED
bulb depicted in FIG. 1;
FIG. 10 is a photograph showing a right side view of the
LED bulb depicted in FIG. 1;
FIG. 11 is a photograph showing a top view of the LED bulb
depicted in FIG. 1; and
FIG. 12 is a photograph showing a bottom view of the LED
bulb depicted in FIG. 1.
The broken lines showing in the figures are for illustrative
purposes only and form no part of the claimed design.
